UNITED STATES PATENT OFFICE.

ALFRED M. THOMAS, OF FORT MORGAN, COLORADO.

PHOTOGRAPHIC-PRINTING MACHINE.

Application filed March 13, 1924. Serial No. 698,976.

To all whom it may concern:

Be it known that I, ALFRED M. THOMAS, a citizen of the United States, residing at Fort Morgan, in the county of Morgan and 5 State of Colorado, have invented certain new and useful Improvements in Photographic-Printing Machines, of which the following is a specification, reference being had to the accompanying drawings.

10 This invention relates to the art of photography, and particularly to photographic printing machines.

The general object of this invention is to provide a photographic printing machine 15 adapted to be used in shops where a large number of prints are made from one negative, though the machine might be used where the negatives were more or less constantly changed, in which the sensitized 20 sheets, such as postal cards and the like, are moved one by one from a magazine disposed in contact with the negative, then removed from contact with the negative and dropped into a receptacle, from which they may be 25 afterwards collected for development.

A further object is to provide a construction of this character in which the sensitized sheets from the time that they are taken from the magazine until the time that they 30 are dropped into the negative box are not touched by the fingers.

A still further object is to provide a machine of this character using suction operated means for picking up and carrying the 35 sheets from one position to another.

Another object is to provide a magazine and automatically operated means for separating the top sheet from subjacent sheets 40 therein so as to permit the suction operated carrier to pick up only the top sheet.

Still another object is to provide means for automatically holding the sheets in proper registry with each other.

A further object is to provide for yieldingly supporting the sheets in the magazine so as to secure a good contact between said 45 sheets and the suction means for lifting the sheets.

A further object is to provide a sheet carrier comprising a bellows mounted for movement from a position over the magazine where it picks up a sheet to a position upon the printing frame and vice versa, and provide means automatically operating the 50 bellows to suck the sheet thereagainst when it is in one position, holding the bellows open

while transferring the card to the printing frame or printing position, and collapsing the bellows as it passes above the sheet receiving compartment to thereby drop the 60 sheet at this time, the bellows remaining collapsed until it reaches and engages with a fresh card or sheet in the magazine.

Other objects have to do with the details of construction and arrangement of parts as 65 will appear more fully hereinafter.

My invention is illustrated in the accompanying drawings, wherein:—

Figure 1 is a side elevation of a photographic printing machine constructed in accordance with my invention, showing the position of the parts when the print is being made and showing in dotted lines the position of the conveying bellows at the time when the print is being discharged; 70

Figure 2 is a top plan view of the construction illustrated in Figure 1;

Figure 3 is a fragmentary plan view of a portion of the frame and the bellows 36, 80 showing the position of the latch 51 when the parts are in the full line position in Figure 1;

Figure 4 is a longitudinal sectional view through the printing machine showing the parts in the printing position; 85

Figure 5 is a longitudinal sectional view on the same lines as Figure 4 but showing the parts in the position in which they are moved when the sheet has been lifted from the magazine; 90

Figure 6 is a section on the line 6—6 of Figure 1;

Figure 7 is a perspective view of the sheet-retainer;

Figure 8 is a fragmentary perspective 95 view of the means for feeding the sheets one by one upward in the magazine.

Figure 9 is a perspective view of the main magazine;

Figure 10 is a sectional perspective of the 100 main magazine with an auxiliary magazine inserted therein to reduce the size of the main magazine.

Figure 11 is a side elevation of the transfer bellows in the position it takes just before the bellows is released as it moves down onto the magazine; 105

Figure 12 is a like view to Figure 11 but showing the position of the bellows when it is released and the bellows moved upward 110 from the magazine toward the printing frame;

Figure 13 is a like view to Figures 11 and 12 but showing the bellows in position over the printing frame and held from entire expansion;

- 5 Figure 14 is a like view to Figure 13 but showing the bellows moving away from the printing frame toward the magazine and showing how the bellows is released to permit its expansion;
- 10 Referring to the drawings, it will be seen that my printing machine comprises a supporting frame including a table or platform 10. This platform defines a longitudinally extending opening upon its under face, and 15 disposed below the platform and within the supporting frame and at what will be termed the rear end of the machine there is a printing compartment or cabinet 11 having side walls and a rear wall and, if necessary, having a front wall. Within this compartment there is provided a lamp, preferably an electric lamp, 12 which may be mounted upon the wall 13, as indicated, or may be mounted in any suitable manner, and it is to be remarked that this light may burn continuously, if desired, or means be provided whereby the light may be turned on when exposures are being made and turned off when the exposures are not being made.
- 20 Immediately rearward of the wall 13 there is a receiving compartment 14 which receives the cards or sheets after they are printed, this receiving compartment being defined by a wall 15 at its forward end and by a side wall. One end of the receiving compartment is preferably open so as to permit the operator to reach in and collect the cards or sheets therefrom for removal to the developing bath.
- 25 30 Immediately rearward of the wall 15 of the receiving compartment there is disposed a magazine 16. This has a front wall and opposed side walls, one of the side walls being cut away, as at 17. The walls of the magazine extend down through the floor of platform 10, as seen in Figure 4, and operating within this magazine is a plunger 18, the plunger rod 19 of which extends downward into the space below the floor and is preferably bifurcated and connected to two radius rods 20 which are pivoted to the plunger and extend laterally and are pivotally supported by a bracket 21 depending from the table (see Figure 6). The means whereby 35 this plunger is raised or lowered will be later explained. One end of the platform 10 above the compartment 11 is formed with a seat 22 to support a negative, which may be either a plate negative or a film negative supported in turn upon a sheet of glass, this transparent plate or negative support being designated 23.
- 40 45 50 55 60 65

For the purpose of carrying a sheet or card from the magazine 16 over to and pressing this card or sheet down upon the film-

carrying plate 23, I provide a bellows 24 which is mounted upon a supporting frame or base 25. The bellows consists of the supporting frame 25, the movable frame or wall 26, and the intermediate accordion-plaited 70 portion 27. The supporting frame 25 is rectangular in form and carries the downwardly protuberant, slightly convex pad 28 which may be made of leather or like material having a plurality of perforations 29 arranged 75 over an area not greater than that of the smallest card or sheet to be printed. This frame 25 is mounted at its forward end upon the downwardly extending links 30, there being two of these links on each side of the 80 frame, each of the links being pivoted at its upper end to the frame 25 and at its lower end extending into a slot in the table and being pivoted to the table.

Likewise supporting this frame 25 are a 85 pair of links 31 extending parallel to the links 30 and pivoted at their upper ends to the frame 25 and at their lower ends inserted in slots in the table 10 and pivoted to the body of the table. Thus it will be seen that 90 while the bellows may move in an arcuate path, the bottom 28 of the bellows always remains in a horizontal plane. A handle 32 is mounted upon the bellows at the rear end thereof and preferably mounted upon the 95 bellows frame itself by two arms 33, and it is by means of this handle that the bellows is carried from its card-engaging position to its printing position and vice versa.

For the purpose of lifting the topmost 100 card in the magazine and detaching this topmost card from the subjacent cards, I provide a bellows at the front of the machine comprising a fixed back 34, the movable back 35, and the intermediate accordion- 105 plaited bellows proper 36. The back 35 is pivotally mounted upon a transverse cross bar 37 mounted between the uprights 38 which form part of the frame. Extending from the rear wall 34 of the bellows and 110 projecting over the magazine adjacent one end thereof is a laterally adjustable hollow nose 39 which at a point immediately over the magazine opens into a shallow box-like head 40 which has a square opening 41 on 115 its under face. Attached to the front and rear walls of this bellows is a leaf spring 42 which acts to urge the two walls toward each other.

For the purpose of automatically closing 120 the bellows 36 as the card carrier moves rearward to a position over the printing frame, I pivot to one of the links 30 the longitudinally extending link 43. This link at 125 its forward end is angularly bent and at the junction of the angular portion with the straight portion of the link I form the notch 44 which engages over a pin 45 projecting from the front wall of the front bellows. The angular portion of the link 43 rests 130

within a longitudinally extended U-shaped sleeve 46 which is mounted upon the front wall 35 of the bellows 36, this sleeve constituting a guide for the rear end of the link.

5 Depending from the link 43 just rearward of the notch 44 is a rigid strip 47 which operates within a slot 48 formed in a latch 49 (see Figure 3). This latch consists of a longitudinally extending plate of metal 10 operatively pivoted at 50 upon the table 10, the rear end of the latch being formed with a relatively wide head 51. The forward end of the latch forward of the pin 50 is slotted at 48, as previously described, and this slot 15 48 is a cam slot and curves gradually laterally adjacent its forward end. Attached to the wall 34 of the bellows 36 is a plate 52 which constitutes a keeper for the latch end 51 of the member 49. Stops 53 limit 20 the rearward movement of the forward wall 34 of the bellows.

When the card lifting bellows 36 moves rearward to bring the head 40 into position over a card in the magazine, the link 43 is 25 released from its engagement with the pin 45 by a member 115 and the arm 47, as will be later stated, and this allows this bellows 36 to expand, drawing up a card. The rearward movement of the forward 30 wall of the bellows 46, this movement being a turning movement upon the pivot 37, causes the vertical downward movement of the wall 34 of the bellows 36, this wall coming in contact with the stop 51 so that it 35 cannot move any more forward and, therefore, moving downward, and when the bellows 36 expands by the release just described, the forward wall will move vertically upward because it cannot move rearward 40 on account of the stop 51 engaging the shoulder 52. Now as the bellows 24 is moved upward and forward, the link 43 will be moved forward. At this time the latch end 51 of the latch 49 is turned inward against 45 the edge of the keeper 52, as before remarked. As the bellows 24 continues to move rearward, however, the arm 47 moving in the cam slot 48 acts to turn the forward end of the cam inward or toward the bellows, releasing the rear end 51 from engagement 50 with the keeper 52 on the rear end of the bellows 14, and at this time the arm 43 will have moved forward sufficiently so that the notch 44 will drop into engagement with the pin 45. At this time the cam has 55 released the rear end of the bellows and, therefore, the whole bellows will swing rearward and downward upon its pivot so as to carry the nose upward and outward away from its position immediately over the magazine and out of the way so that the bottom of the bellows 24 may come down flat upon the upstanding walls of the magazine. Upon the reverse movement given to bellows 27, 60 the bellows 35 will swing bodily upward 65

until its rear wall 34 is in an approximately vertical position. When the forward wall is nearly in this vertical position, the rear wall will engage the stop 53, which will limit the forward movement of this rear 70 wall. At this time the cam arm 47 has entered the slot 48 and as the rear wall 34 passes the end 51 of the latch, this arm 47 swings the latch end 51 inward in front of the keeper 52, thus again latching the 75 rear wall 34 of the bellows 36 into vertical position. Thus as the bellows 34 moves toward the magazine, it will be completely compressed and then suddenly expanded.

It will be seen that this mechanism, therefore, provides for a partial expansion of the bellows 36 upon the first part of the movement of the card carrier bellows 24 and then a movement of the bellows 36 from its position with the nose thereof extending over the magazine to a position with the nose extending up into the air.

Mounted upon the rear wall 34 of the bellows 36 is a leaf spring 54 which, when the wall 34 is in a vertical position, bears 90 resiliently against the pack of sheets or cards disposed upon the plunger 39. Disposed immediately above the spring 54 is a relatively short nozzle 55.

Mounted in bearings upon the table is a 95 transverse rock shaft 56, the intermediate portions of which are formed with upwardly extending fingers 57 and this rock shaft is resiliently maintained with the fingers extending over the top of the plunger 18 by 100 means of a spring 58 which is attached to an arm extending from the rock shaft. It is necessary to oscillate the rock shaft so as to raise the fingers from their position overhanging the plunger and the cards or sheets 105 thereon, and to that end I attach to the arm 59 the rod 60, this rod extending rearward and being connected to a lever 61 (see Figure 2) pivoted at 62 to the table, this lever at one end having a plurality of apertures, 110 within one of which this rod 60 may engage. The lever is prevented from moving beyond a certain position by means of a stop 63.

For the purpose of automatically shifting 115 this lever and thereby automatically raising the fingers from their position over the upper end of the magazine, I mount upon the table the cam-like member 64 formed of a plate of metal with a sector-shaped opening 120 extending radially inward and having upstanding walls 65 and 66. This plate 64 is pivoted at 67 and is so disposed that one of the walls 65 or 66 is always in the path of movement of the rearmost link 31 on one 125 side of the machine. Thus as this link 31 moves forward so that the bellows 36 is carried to a position over the magazine, the link will turn the cam 64 by engagement with the wall 65 and this wall 65 in turn will engage 130

with the lever 61 and shift the lever so as to cause the rock shaft 56 to rock in a direction to carry the fingers away from the position over the magazine. On the other hand, 5 when the bellows carrier 24 moves rearward, the link will strike against the wall 66 and lift the cam in the other direction, whereupon the spring 58 will draw the rock shaft in position to carry the fingers again above 10 the magazine.

At the time that the lifting of the bellows 35 operates to suck up one end of a card or sheet from the pile of cards or sheets lying upon the plunger, it is necessary to insert a 15 separator between the lifted end of the card or sheet and the subjacent sheets, and to this end I mount upon the front wall 35 of the bellows 35 an angularly disposed, relatively short channel iron 68. This channel iron is 20 disposed to extend rearward and outward and is rigidly mounted upon the front wall of this front bellows. Oscillatably mounted upon the platform is an arm 69, the rear end of which is angularly bent and extends downward 25 and oscillates within a suitable socket formed in the table, this arm extending forward and being disposed normally against the side of the back 34 of the card lifting bellows. A spring 70 urges this rod inward 30 and the rod carries upon it a finger 71 whose extremity is beveled and which passes through an opening formed in one side wall of the magazine.

When the card carrying bellows is moved 35 forward by means of the handle 32, the card lifting bellows, as before stated, swings upon its pivot and as soon as the channel iron cam 68 has left the extremity of the arm or rod 69, this arm swings inward under the impulse of the spring 70 and the separator 71 or finger is inserted between the partially lifted card held up by the lifting bellows and the subjacent card. Thereafter when the lifting bellows moves still further rearward, 40 one end of the card will be held above the other cards and separated therefrom so that when the card carrying bellows comes down upon the magazine to engage this lifted card, it will lift this one card or sheet and no 45 other and the subjacent cards will be held firmly down against any lifting movement.

When the card carrying bellows is shifted rearward again and the rear wall 35 of the card lifting bellows moves inward, the 50 cam 68 will bear against the rod or arm 69 and shift it outward and this will retract the finger or separator 71 so that the suction head 40 carried on the nose 39 may come in contact with the uppermost card or sheet in 55 position to suck it upward when the lifting bellows is initially expanded.

In order to cushion the downward movement of the card carrying bellows as it nears 60 a position over the printing frame, I provide the leaf spring 72 which is attached to the

table 10 and extends upward and forward and is engaged by the butt end of an arm 73 which is rigidly mounted upon the pintle 74 by which the link 30 is connected to the base 25 of the bellows 24. This arm 73 always 70 maintains the same position of angularity relative to the link 30. Thus when the bellows 24 is drawn over above the printing frame, the arm 73 will be at a slightly obtuse angle to the link 30 and at an acute angle to 75 the table, while when the base of the bellows 24 has been turned over on the magazine, the arm 73 will have a position nearly parallel to the table.

For the purpose of permitting the bellows 24 to partly expand as it moves upward and away from the magazine, and remain partially expanded while it carries the sheet or card onto the glass of the printing frame and be further expanded as it picks the sheet or 80 card up from the glass of the printing frame and carries it into position over the receiving compartment 14, I provide a rod 75 which is pivoted to the end of the arm 73 and extends rearward and passes over a laterally 85 projecting rod 76 mounted upon the upper end of the wall 26 of the bellows 24. This rod 75 is pivoted at one end to the rod 73 and at its other end is formed with a downwardly extending bend 77 constituting a stop 90 and about one-third of the distance from this stop 77 to the point of connection with the arm 73 the rod 75 is formed with a second stop 78. These stops 77 and 78 are adapted 95 to catch upon the outwardly and upwardly projecting pin 76.

Mounted upon the link 30 which is immediately beneath the arm 73 and in fixed angular relation to this link is a rigid arm 79. This arm is adapted to engage, as will 100 be later stated, with the face of the outwardly projecting stop lug 78 so as to push this stop lug off from its engagement with the pin 76.

When the handle 32 is lifted to carry the 105 bellows 24 from a position over the printing frame to a position over the magazine, the first action is to lift the pivoted end of the arm 75. At the same time the movement of the arm 73 tends to pull the rod 74 and bring the angular stop 78 against the pin 79. Therefore, as the bellows 24 moves into a 110 position over the receptacle 14 or from this position, the rod 75 will draw the outer wall of the bellows toward the horizontal wall 115 thereof so as to expel the air from the bellows and this forces down the card or sheet which is clinging to the under face of the bellows. As the bellows nears the upper end 120 of the magazine, the bellows is still further contracted by the action of the arm 73 and of the rod 75 until at a point when the under face of the bellows 24 is immediately 125 over the magazine and just as the bellows touches the uppermost card or sheet held by 130

the magazine, the rod 75 takes such an angular relation to the wall 26 of the bellows that the arm 79 bears against the lug 78, and just as the bellows reaches the face of the card this arm 79 forces the rod 75 upward so as to lift the stop 78 from its engagement with the pin 76 and the bellows will tend to fly open, the stop 77 moving toward the pin 74. As a matter of fact, the bellows does not fly fully open when the rod 75 releases engagement with the pin 76 because of the fact that there is a card which is sucked against the under face of the bellows, that is against the cushion 28, and therefore, the bellows can only partially open. Now as the bellows moves upward and forward, the rod 75 slides upward over the pin 76 until the stop 78 passes to a point beyond this pin.

As before remarked, the bellows tends to fully expand but this is prevented by the fact that there is a card against the under face of the pad of the bellows, but as the bellows moves over toward the printing frame and finally moves down upon the printing frame, if the bellows was allowed to expand air would leak in between the card and the pad, for instance, and thus the bellows would exert no suction on the card for a reverse movement of the bellows which would carry the card into position where it may be dropped into the card receptacle. In order to prevent this, the upper frame 23 of the bellows 24 has attached to it adjacent one edge the annular arm 80, one end portion of which extends straight downward when the bellows is in this partially expanded position and is nearing a position over the magazine and is in position over the printing frame so that when the bellows nears the printing frame, the lower end of this arm 80 will strike against a triangular-shaped stop 82 mounted upon the base 10 and thus will prevent the full opening movement of the bellows so that the bellows at the time it arrives over the printing frame is held in a partially open position against the action of a spring 80 which urges the bellows 24 to an expanded position. This spring is mounted upon the under wall 25 and extends upward and over the back 26 and at its free end is connected to a hook 80^a mounted upon the upper edge of the wall 26 of the bellows. As the bellows is about to be moved off from the printing frame to carry the printed card back into position over the receptacle 14, the arm 81 will move away from the stop 82 and hence the bellows will then more fully open under the action of the spring 82, which will cause the suction induced by the action of the bellows to draw the card lying on the plate of the printing frame into close engagement with the pad 28 and this card is so held until the bellows is disposed over the receptacle 14, where the frame 26 of the bellows is

moved downward by means of the rod 75, as heretofore described, so as to discharge the card forcibly from its engagement with the bellows and force the card to drop into the receptacle 14.

As before stated, it is necessary when the carrier bellows moves over onto the top of the magazine that the plunger be raised so as to carry the pack of cards or sheets upward into such a position that the suction of the bellows 24 will suck the card or sheet up against the under face of the pad 28, and it is also necessary that the plunger should move downward as the bellows 24 moves into position over the printing frame so that the uppermost card may be separated from the lower card and be engaged by the separator 71 and thus held lifted from the subjacent cards.

The mechanism whereby this is accomplished is as follows: The plunger rod 19 is pivotally connected to the radius rods 20, as previously stated, and also mounted upon the lower face of the plunger 18 is an eye 83^a, with which eye is engaged the vertical rod 83. This rod extends downward and has sliding engagement with a supporting brace 84 extending between the front of the frame and the wall 15 of the compartment 14. This brace 84 is supported by a stirrup 85, though I do not wish to be limited to this.

Mounted upon the rod 83 is a U-shaped yoke 86 having apertures at the ends of its arms through which the rod 83 passes. Mounted to one side of this yoke 86 and disposed in the brace 84 is the vertical guide rod 87. Disposed between the arm of the U-shaped yoke 86 is an approximately U-shaped clamp 88. The end of the clamp which is disposed between the arms of the yoke 86 is enlarged and rectangular in form and is designated 89, and at its junction with the curved portion 90 of this clamp there is formed an elongated slot 91 through which the rod 83 passes. The arm 92 of the clamp is not parallel to the portion 89 but is disposed at a slight angle thereto and is also slotted for the passage of the rod 83. The extreme corner of the portion 89 is also slotted for the passage of the guide rod 87. Disposed between this plate-like portion 89 of the clamp and the lower arm of the U-shaped yoke is an upwardly extending plate 93, the inner end of which is hinged, as at 94, to the yoke 86, the outer end having a slot through which the rod 83 passes and there being a spring 95 forcing the free end of this plate 93 upward and into contact with the under face of the clamp 88.

Hingedly mounted at 96 is a downwardly extending rod 97 whose lower end is curved outward and upward, as at 98, and bears against the upper face of the plate-like portion 89 of the clamp. This rod at one end is formed with an eye 99, and pivotally

connected to this eye is the link 100. This link extends upwardly and is in turn pivotally connected to the upper end of a rod 101 which is pivoted at its lower end in the brace 84 so that this rod 101 can swing inward. In swinging inward, it is obvious that it will depress the link 100, which in turn will depress the lever 97 against the plate 89.

For the purpose of securing this movement of the rod 101, which in itself constitutes a lever, I provide a triangular cam 102 mounted upon the inner wall 34 of the bellows 36. One face of this triangular cam has a longitudinally extending groove 15 within which the extremity of the rod or lever 101 travels. A spring 103 is fastened at its upper end to the frame of the magazine and at its lower end is attached to the U-shaped yoke 86 and acts to draw this yoke 20 upward. A leaf spring 104 is attached to a cross bar on the frame of the machine and has its free end extending beneath this U-shaped yoke 86, this free end being apertured for the passage of the guide pin 87. 25 A guide pin 105 prevents the curved portion 98 of the arm 97 from slipping off the plate 89.

With this construction, it is obvious that as the carrying bellows 24 is shifted from 30 the magazine, the rear wall 34 of the bellows 36 will move inward and eventually the cam 102 will strike the upper end of the rod 101 and shift this rod on its pivot, thus depressing the link 100 and the part 97. This will 35 cause a rocking of the plate 89 which will lock, therefore, upon the rod 81 and the clamp 90 and the rod 81 will descend together, thus carrying the plunger downward. The plunger will remain downward until 40 the cam 102 moves out of its engagement with the rod 101, whereupon the spring 106 will cause the plunger to lift fully upward so as to press the cards upward against the pin or separator 71. At the time the cam 45 102 moves out of its engagement with the rod 101, the springs 104 and 103 will cause the lifting of the clamp which will release the plunger so that the plunger under the action of the spring 106 will move fully upward. This spring 106 is attached at its 50 lower end to a supporting member 106^a upon which the outer end of the lowermost arm rests. The upper end of this spring is attached to the under face of the table. It 55 will be understood that the pad on the under face of the bellows 24 never touches the cards in the magazine but only moves near enough to the card in the magazine to suck the uppermost card upward into contact 60 with the bellows and, therefore, this pad on the under face of the bellows 24 does not cause any downward pressure of the cards in the magazine.

The clamp and plunger mechanism shown 65 in Figure 8 is particularly important. It

would be a relatively easy matter to secure a plunger that would merely work up and down vertically, but the necessities of the present case require that the plunger shall hold the cards in proper position a proper 70 length of time and then release them at the proper instant as well. There are times when the magazine will be filled with one, two or three hundred cards or even a greater 75 number of sheets of paper and it is necessary that the plunger should be urged upward so as to shift this paper up against the pin 70 and then that upon a movement of the bellows away from the magazine the cards should be moved downward and the plunger 80 should be moved downward. The clamp acts to shift the plunger downward upon an outward movement of the bellows 36 and a retraction of the pin and then when the pin 70 has been put back in place again so 85 as to separate the uppermost card from the next succeeding card, the action of the parts is to release the plunger and permit it to move upward under the action of the spring and force the cards back up against the pin 90 and this without regard to the number of cards which may be in the magazine.

The magazine 16 is rectangular in plan and has an area that of a standard photographic print, as 3 1/4 x 4 1/4, 5 x 7, or like dimensions, and it is intended that adapters shall be furnished with the machine, each adapter nesting within the next larger size and these adapters being insertible within the magazine to restrict the dimensions 95 thereof from the maximum size. Such an adapter is shown in Figure 10 and designated generally 16^a. This adapter is the same as the magazine itself, except that the rear wall consists of a thin plate of metal 100 110 formed with a medially disposed flange 111 at its upper end adapted to fit over the rear wall of the regular magazine, the wall on each side of this middle portion being lowered and formed with outwardly extending flanges 112 and 113. The rear wall of the magazine at one end is formed with the upwardly and inwardly extending hook 114, and the flange 113 is cut out to fit over 110 this hook. This hook 114 is designed for 115 preventing any card sucked up by the suction head 40 from being carried upward and rearward beyond the magazine. In order to adjust the suction head 40 to changes in the magazine by the insertion of the adapter or the removal of the adapter, the nozzle 39 is mounted upon a plate 115, which plate is mounted in guides 116 attached to the wall of the bellows 36 so that this plate may be shifted longitudinally to dispose the nozzle 120 in its new position to adapt it either to the large magazine or the relatively smaller magazine. This plate is held in place by any suitable means as, for instance, the clamp 125 117.

- The operation of this mechanism, generally speaking, is as follows: The magazine is to be filled with sensitized cards as, for instance, sensitized postal cards disposed, of course, with the sensitized face downward. When the magazine is filled (which may be done when the conveying bellows 24 is elevated), the handle 32 is operated to shift the bellows 24 over toward the magazine.
- 5 As the bellows 24 is shifted over toward the magazine from its most elevated position, the rod 75 will cause the operation of the bellows. At the same time the bellows 24 is moving over toward the magazine, the bellows 37 is moving away from the magazine and has acted to pick up a card in the manner described at one end so that the separating finger may be inserted between this card and the subjacent cards. The first movement 10 of the bellows 37 is to expand the bellows and this acts to suck a card upward against the suction head. Then when the bellows has fully expanded, the swinging action of the bellows 37 takes place, which moves the nose 39 and the suction head 40 away from the magazine. As the bellows 24 moves downward toward the magazine, it becomes compressed through the action of the rod 75, and when the bellows has arrived at such 15 point that the pad 28 on the under face of the bellows strikes the card, the stop 78 will slip off the hook 76. As soon as this occurs, the spring 80 on the bellows tends to cause the bellows to open and the bellows 20 opens as far as is permitted by the fact that there is a card bearing closely against all the openings on the under face of the pad of the bellows. This opening of the bellows 25 draws the card up into contact with the pad 28 so that the card is then held against the under face of the pad and as the carrier bellows is moved over the card will be carried with it. As the carrier is moved over, the rod 75 slips along the hook 26 until 30 eventually the stop 28 drops over the hook 79. Meanwhile the bellows 24 is moving over so as to carry this pad into a position parallel to and immediately above the glass of the printing frame. By the time that the pad 28 has moved into position over the printing frame, the bellows is tending to open, but it cannot do so because of the fact that the arm 80 bears against the stop 81 at this time so that the bellows cannot open 35 any further and thus lose its air before the bellows is to be moved to carry the card from a position over the printing frame to a position over the receptacle into which the card has dropped.
- 40 Attention is called to the fact that if no means such as the members 81 and 82 were present to prevent the complete opening movement of the bellows 24 when the bellows 24 was moved over into position on the printing frame, then this device could only be used for the printing of negatives having a slight density and requiring but a minimum of exposure, but by providing means to prevent the full opening of the bellows at the time when it moves over upon the printing frame, negatives of any density may be printed without the bellows losing its suction, that is the members 81 and 82 arrest the motion of the bellows for any duration of time, but the moment, however, that the bellows is picked up and moved away from the printing frame, the suction immediately lifts the card and, of course, delivers it to its proper receptacle. This allows for variations in densities in different negatives, it being obvious that one negative might be printed in a second, where another negative of a different density might require several seconds to print.
- 45 While the bellows 24 is moving from its highest position downward toward the printing frame, the card lifting bellows composed of the parts 34, 35 and 36 swings upon its pivot 77 to a position where the front wall 34 of the bellows is vertical and the nose is extended over the top of the magazine. As the bellows 24 moves downward toward the printing frame, the rear wall 35 of the lifting bellows closes toward the front wall, urged thereto by a pull of the connecting rod 43, so that the lifting bellows is now collapsed and remains collapsed until the transferring bellows 24 has almost reached its position over the printing frame, but the lifting bellows is released just before the 50 transferring bellows reaches the printing frame. This is secured by providing a lifting wedge or incline 115 immediately below the base end of the slot 48 and the latch 49 and the arm 47 in its passage through the cam slot 48 rides up on this incline 115, thus releasing the notch 44 from its engagement with the pin 45, whereupon the spring 42 immediately opens the bellows. The opening 55 of the bellows causes suction to be applied to the topmost card of the magazine through the suction head 40 and the card is raised and held raised at one end. As the card is raised by the suction created by the opening of the bellows 35, the finger 71 swings inward beneath the margin of the card so that as the head moves backward upon a return of the transfer or carrier bellows to the magazine, the uppermost card will be held 60 separated from the other cards of the pack.
- 65 It will be seen that the card is carried up by the suction head of bellows 36. In other words, the card adheres to the suction head. The suction, when the bellows is opening, causes the card to fly up and adhere to the suction head, and when the bellows ceases to open, the suction ceases and the card will then drop off from the suction head. Thus it will be obvious with the bellows so regulated 65 as to cease opening in any position, it will 70

cause the card to drop off, but in case the card is jerked up very suddenly by a sudden retractile movement of the bellows 36, the hook plates on the top edge of the magazine 5 will knock the card off and cause it to drop.

As the bellows 24 moves upward and rearward by lifting upon the handle 32, the rod 43 will also move rearward but without affecting the bellows 34, 35 and 36 until the 10 notch 44 engages the pin 45. At this time the arm 47 is moved to the extremity of the cam slot 48 and shifts the cam away from its engagement with the keeper 52. The further movement of the link 30 causes the backward 15 swinging movement of the card lifting bellows. As the transfer bellows moves from its position over the printing frame, it retains the card until the bottom of the transfer bellows is immediately over the receptacle 20 for the exposed cards and at this time the bellows 24 is slightly compressed by the action of the connecting rod 75 and this dislodges the card from the under side of the bellows and causes the card to drop into the 25 receiving box.

Attention is particularly called to the parts shown in Figure 7. These parts 56 and 57 constitute a movable magazine wall which is adjustable to all changes in width 30 of the several magazines from, for instance, 5 x 7 to 2 1/4 x 3 1/4. If this magazine wall constituted by the parts 57 was a permanent fixture, the paper-carrying bellows 36 would in its backward and upward movement pull 35 the paper against the wall and positively move it or knock it entirely off the pad. Hence it is necessary that the magazine wall be movable and also be adjustable. For this reason the rock shaft 56 may be shifted 40 into one or more bearings 59, as shown in Figure 1 and Figure 4, so that the rock shaft may be moved nearer to or further from the paper mounted on the plunger head 18, and it is also necessary that the 45 arm 61, as shown in Figure 2, be provided with a plurality of openings for engagement with the link or connecting rod 60 to thus adjust the movement of this wall 57.

It will be obvious that the operation may 50 be repeated as many times as desired and that during the entire operation the fingers will not touch the card in any manner. The entire manipulation of the card is secured by suction, and inasmuch as no hands touch 55 the card itself, it follows that unskilled labor may be used for printing the card, it being merely necessary to hold the carrier bellows and the card down on the printing frame a certain predetermined length of 60 time. The rest of the operation is automatic.

With regard to the construction of the clamping mechanism shown in Figure 8, it is particularly pointed out that the clamp 65 causes the plunger to work up and down, holds the cards in proper position and for

the proper length of time, and then releases them at the proper instant as well. In order to explain this, it may be stated that the top card is elevated above the middle at one end when the bellows 24 starts 70 forward, that is elevated by means of the pin 71, as shown in Figure 6. This card is not in a proper position, however, at that instant but as bellows 24 continues to move forward, the bellows 36 releases the 75 clamp shown in Figure 8, that is the cam 102 moves away from the rod 101 and this levels the top card and properly positions it. When the top card becomes level, at that instant the bellows 24 rides over the plunger 80 just in time to suck the card up the very instant it reaches its level position. The bellows 36 is locked by lock 48 and held by this lock 48 until the right instant arrives, when lock 48 releases the bellows 36 and the bellows 36 in turn releases the clamp. When bellows 36 moves over into position above the magazine, the clamp and the plunger do not move. When bellows 36 starts to move away from this position, however, 85 the plunger still does not move while the bellows 36 is opening, but the instant that the nose 39 lifts the top card while the bellows 36 is opening, then the lock which holds the plunger is released. The back wall of bellows 34 or bellows 36 continues to move over and this releases the clamp, which allows the plunger to raise the cards against the pin 71.

I have referred to the construction illustrated in Figure 7 consisting of the members 56, 57 and 59 as being fingers. It will be understood that, as a matter of fact, the parts 57 together constitute a wall disposed in front of the magazine, this wall being shiftable so as to permit the paper carrying bellows in its backward and upward movement to draw the paper against the wall but yield to permit the retraction of the paper.

While I have illustrated a construction which has been found to be effective in practice, I do not wish to be limited thereto as it is obvious that many changes might be made in the details of the device and the arrangement of parts without departing from the spirit of the invention.

I claim:—

1. A photographic printing machine including a printing frame, a magazine for sensitized paper, means for shifting the sensitized sheet from the magazine to the printing frame and then releasing the sheet comprising a support, a member having linked connections with the support and having a handle whereby it may be shifted, said member having a suction device upon its under face, a bellows connected to the suction device, and means for causing the automatic inflation of the bellows when in 120 125 130 135 140 145 150 155 160 165 170 175 180 185 190 195 200 205 210 215 220 225 230 235 9990 9995 10

position to pick up a sensitized sheet from the magazine and the automatic deflation of the bellows when it reaches a position where the sheet is to be discharged after 6 the sheet has been disposed against the printing frame.

2. In a photographic printing apparatus, a printing frame, a magazine adapted to contain sheets of sensitized paper, a compartment for printed sheets disposed between the magazine and the printing frame, means for shifting a sensitized sheet from the magazine to the printing frame comprising a supporting member, a member 10 having linked connection with the supporting member and having a handle whereby it may be shifted, said member carrying a sheet-engaging suction device, a bellows connected to the member, and means for causing 15 the automatic inflation of the bellows when the handle has been shifted to carry the suction device over the magazine or the automatic deflation of the bellows when the handle has been shifted to carry the suction 20 device to a position above the compartment for printed sheets.

3. In a photographic printing machine, a printing frame, a magazine, a compartment for printed sheets disposed between 30 the magazine and the frame, a member manually movable from a position over and upon the magazine to a position over and upon the printing frame and vice versa, said member having a perforated pad upon its 35 under face, and suction operated means acting to draw a sheet of paper against said pad while the pad is disposed over the magazine, retain said paper against the pad while the pad is moving to and over the 40 printing frame and again toward the magazine and release said paper when the pad is over the compartment.

4. A photographic printing machine including a printing frame, a magazine 45 adapted to contain superposed sensitized sheets, a compartment for receiving sheets after they are printed, manually shiftable pneumatic means for lifting the sheets one by one from the magazine and carrying 50 said sheets to a position over the printing frame, holding them in position on the printing frame while being printed, and carrying said sheets into a position over the compartment and discharging the sheets, 55 and means for lifting the top sheet in the magazine into delivery position automatically as the pneumatic lifting means nears the magazine.

5. In a photographic printing machine, 60 a printing frame, a magazine, a compartment between the magazine and the printing frame designed to receive printed sheets, a member having a suction device in one position disposable upon the top of the magazine and in another position disposable

over the top of the printing frame, a bellows carried by the member, means for causing the automatic expansion of the bellows when it reaches a position immediately over the magazine, said means causing the retaining 70 of said expansion while the bellows is moving from the magazine to the printing frame and while it is resting upon the printing frame, and means for causing a contraction 75 of the bellows and the consequent detachment of the sheet from the suction device when the perforated member is over the sheet receiving compartment.

6. In a photographic printing machine, 80 a supporting frame, a printing frame arranged within the supporting frame, a magazine mounted within the supporting frame and adapted to contain sensitized sheets, there being a compartment disposed between the magazine and the printing frame, a sheet transferring member including a suction device, parallel links pivoted to the supporting frame and to said member whereby the member may be manually moved from a position over the magazine 85 to a position over the printing frame, a bellows mounted upon and forming part of said member, means for automatically causing the expansion of the bellows as it reaches a position over the magazine and retaining 90 said expansion while the member is moving from the magazine into position over the printing frame and while said member is moving from the printing frame to a position over the receiving compartment and 95 means for then causing the contraction of said bellows to cause the detachment of the sheet from the under face of the suction device and the discharge of the sheet into the 100 compartment.

7. In a photographic printing machine, 105 a supporting frame, a printing frame arranged within the supporting frame, a magazine mounted within the supporting frame and adapted to contain sensitized sheets, there being a compartment disposed between the magazine and the printing frame, a sheet transferring member including a suction device, parallel links pivoted to the supporting frame and to said member whereby the member may be manually moved from a position over the magazine to a position over the printing frame, a bellows mounted upon and forming part of said member, 110 means for automatically causing the expansion of the bellows as it reaches a position over the magazine and retaining said expansion while the member is moving from the magazine into position over the printing frame and while said member is moving from the printing frame to a position over the receiving compartment, means for then causing the contraction of said bellows to cause the detachment of the sheet from the under face of the suction device and the 115 120 125 130

discharge of the sheet into the compartment, a plunger mounted within the magazine and supporting the sheets therein, and resilient means yieldingly urging said plunger upward as the transferring member reaches a position over the magazine.

8. In a photographic printing machine, a magazine adapted to contain sensitized sheets, a plunger operating therein, a printing frame, a compartment disposed between the printing frame and the magazine adapted to contain printed sheets, manually shiftable pneumatic means for lifting a sheet from the magazine, transferring the sheet to the printing frame holding it thereon and transferring it to a position above the compartment and discharging the sheet thereinto, and means acting to automatically lift the uppermost sheet of those disposed in the magazine and hold said sheet separated from the subjacent sheets until picked up by the transferring member.

9. In a photographic printer, a supporting frame, a magazine mounted thereon and adapted to contain sensitized sheets, a printing frame mounted thereon and having illuminating means, a compartment disposed between the magazine and the printing frame and adapted to contain printed sheets, a sheet transferring member comprising a base having a perforated pad, a bellows attached to the base and having a hinged back, a handle connected to said base, links pivotally connected to the base and to the supporting frame whereby the base may be shifted from a position immediately over the magazine to a position immediately over the printing frame, means causing the automatic expansion of the bellows as it reaches a position over the magazine to thereby cause suction to be applied to the uppermost sheet in the magazine, and means causing the deflation of said bellows when the supporting member thereof is immediately over the said compartment and is being moved from the printing frame to the magazine.

10. In a printing frame, means for shifting a sensitized sheet from one position to another comprising a supporting frame, a member having linked connection with the supporting frame and having a handle whereby it may be shifted, said member having a perforated pad upon its under face, a bellows connected to the member, and means for causing the automatic inflation of the bellows when in position to pick up a sensitized sheet and the automatic deflation of the bellows when it reaches a position where the sheet is to be discharged.

11. In a photographic printing machine, a magazine designed to contain sensitized sheets, a printing frame, an intermediate compartment designed to receive printed sheets, a sheet transferring mechanism comprising a member having a suction device

upon its under face and adapted to be disposed flat upon the top of the magazine or upon the top of the printing frame, a supporting frame for the magazine and the printing frame, links pivotally connecting said member to the supporting frame, a handle on said member whereby it may be shifted, a bellows mounted upon the member and having a back, a spring urging the bellows to an expanded position, means for automatically causing the expansion and contraction of the bellows comprising a pin extending outward from the back from one edge, an arm forming an angular extension of one of said links, a link pivotally connected to the end of said arm and having an angular stop intermediate its ends and an angular stop at the extremity of the link and engaging over said pin, and a lug extending outward from the back to such position that as the bellows reaches a position over the magazine the link will be lifted to disengage its intermediate stop from the pin and permit the expansion of the bellows under the action of the spring.

12. In a photographic printing machine, a supporting frame, a printing frame, a magazine designed to contain sensitized sheets, manually shiftable suction operated means for transferring the sheet from the magazine to the printing frame, and suction operated means for lifting the top sheet in the magazine into delivery position and operated by a movement of the manually operable means into proximity to the magazine.

13. In a photo-printing machine, a supporting frame, a printing frame mounted thereon, a magazine mounted thereon and open at its upper end, a compartment for receiving printed sheets disposed between the magazine and the printing frame, a plunger within the magazine, a suction operated transferring device operatively mounted upon the supporting frame for movement from a position over the magazine to a position over the printing frame, suction operated means for lifting the top sheet of the series of sheets in the magazine into delivery position, the suction operated means being movable out of position above the magazine upon a movement of the transferring member from the printing frame to a position above the magazine, means for yieldingly urging the plunger upward as the transferring member moved from a position over the printing frame to a position over the magazine, means for causing a return of the suction operated lifted means to a position over the magazine upon a movement of the transferring member from the magazine to the printing frame, and means then acting to depress the plunger.

14. In a photo-printing machine, a supporting frame, a printing frame carried

thereby, a vertically disposed magazine and a vertically disposed receptacle between the magazine and the printing frame and adapted to receive printed sheets, a transfer member operatively mounted upon the frame and including a bellows, a front therefor having a perforated pad adapted to rest flat upon either the magazine or the printing frame, the bellows having a movable back and having a handle whereby it may be manually shifted from a position over the magazine to a position over the printing frame or vice versa, means for lifting the first sheet of the series of sheets in the magazine and holding the sheet raised into position to be engaged by the transfer member, said means comprising a bellows having an outstanding nose with a suction head, the bellows being mounted for movement into or out of a position with the suction head immediately above the magazine, means for automatically shifting the last named bellows into position with the suction head above the magazine as the transfer member is moved from the magazine to the printing frame, means for compressing the second named bellows as it moves into a position with its nose over the magazine and then releasing the second named bellows to permit its immediate inflation, a spring urging the bellows to an expanded position, a separator mounted for reciprocation through one side wall of the magazine adjacent the top thereof and urged inward into the magazine, means on the second named bellows causing the separator to move out of the magazine as the suction head is disposed immediately above the magazine but permitting the inward movement of the separator when the suction head is moved away from the magazine and the transfer member is moved into position above the magazine.

15. In a photographic printing machine, a supporting frame, a printing frame mounted thereon, a magazine having back and side walls and extending upward above the supporting frame and spaced from the printing frame to provide an intermediate receptacle into which printed sheets may be discharged, feeding mechanism disposed within the magazine, a transfer device comprising a base, links pivotally connecting the base to the supporting frame and permitting the base to be shifted from a position immediately above the magazine to a position over the printing frame and vice versa, the base having a pad with perforations, a bellows mounted upon the base, a back member hingedly connected to the base and to which the bellows is attached, a spring urging the bellows to an expanded condition, a handle attached to the base and whereby the base may be shifted from a position over the magazine to a position over the printing frame and vice versa, a second bellows having a back wall and a front wall, the back wall being pivotally mounted upon the supporting frame and the back wall being hinged with respect to the front wall, a nose extending from the back wall and having a downwardly opening suction head, means acting to shift the second named bellows into position with the suction head immediately above the magazine upon a movement of the transfer bellows from a position over the magazine to a position over the printing frame, means for compressing the second named bellows as the suction head arrives over the magazine and then releasing the bellows to permit its expansion, a spring causing the expansion of the bellows whereby to cause the suction head to lift on the first card of the series within the magazine, means then insertible between the lifted sheet and the next subjacent sheet to thereby hold the sheet lifted, means causing the rearward movement of the second named bellows upon a movement of the transfer bellows from its position over the printing frame to a position over the magazine, a yielding plunger in the magazine resiliently urged upward, and means acting to depress the plunger upon a movement of the second named bellows into position to carry its nose over the magazine.

16. In a photo-printer, a magazine for containing sensitized sheets, a plunger operating therein, manually shiftable means for picking up the topmost sheet, a printing frame to which the transferring mechanism is adapted to transfer the sensitized sheet, means for lifting the top sheet of the series within the magazine into position to be acted upon by the transfer mechanism comprising a bellows having opposed walls, one of said walls being pivotally supported whereby the bellows can swing in a vertical plane, the two walls being hingedly connected to each other to permit the expansion and contraction of the bellows, a nose extending from one wall of the bellows and having a suction head in one position of the bellows being disposed over the magazine at one end thereof, a spring carried by the same wall of the bellows and adapted to extend into the magazine and bear against the opposite end of the sheet, means for causing the bellows to swing outward and away from the magazine but permit the transferring mechanism to engage the magazine comprising a longitudinally extending rod operatively connected to the transfer mechanism, said rod having a notch, a pin on the pivoted wall of the bellows engageable in said notch, a pivoted latch having a cam-shaped slot, the latch being adapted to engage the back wall of the bellows and initially prevent any rearward movement of said back wall when the transfer member moves rearward, and means lifting the rod upward to release the engage-

ment of the pin with the notch when the second named bellows has been moved into position to carry its nose over the magazine.

17. In a photo-printer, a supporting frame, a printing frame mounted thereon, a magazine adapted to support a series of superposed sheets in superposed relation, manually operable means mounted upon the main frame for automatically lifting a sheet from the magazine and transferring said sheet to a position over the printing frame, a rock shaft mounted in front of the magazine and having fingers normally extending upward and inward over the sheets in the magazine, and means for causing the rocking of said shaft to shift the fingers away from said sheets when the transferring member is moved into position over the magazine.

18. In a photo-printer of the character described, a supporting frame, a printing frame mounted thereon, a magazine mounted thereon, an intermediate compartment disposed between the printing frame and the magazine and adapted to receive printed sheets, a transfer member including a base having a perforated pad, links supporting the base at all times in a horizontal plane, said links being pivoted at their lower ends to the supporting frame and at their upper ends to said member, manually operable means for shifting the supporting frame to carry said pad from a position over the magazine to a position over the printing frame, suction operated means acting to lift the topmost sheet from the magazine and carry it to the printing frame and acting when the transfer member is above the receiving compartment to discharge said sheet, a guard mounted in front of the magazine comprising a series of fingers extending inward and over the magazine, means for retracting said guard upon a movement of the transfer device into position over the magazine comprising a lever pivoted upon the supporting frame and having a link connection to the guard, and a member pivotally mounted upon the supporting frame in the path of movement of one of said links and adapted to contact with said lever, said member moving in one direction upon a movement of the transfer member in one direction and be moved into its initial position upon a movement of the transfer member in the opposite direction.

19. In a photographic printing machine, a

platform having a horizontally disposed printing frame at one end and a magazine at the opposite end, the magazine extending vertically from the platform and having its open upper end disposed in a horizontal plane; a manually operable horizontally disposed member movable into position over the magazine or over the printing frame, said member having links pivotally connecting it to the platform whereby movement in one direction will carry it from the magazine to the printing frame.

20. In a photographic printer, a supporting frame having a platform, a support for the negative, a sensitized sheet carrier, a carrier provided with a suction head and vacuum-producing means connected thereto, and operating member for the carrier movable in one direction to carry a sensitized sheet from a magazine to the negative and in the other direction to carry the sensitized sheet from the negative, and means for causing the vacuum-producing means to act upon the suction head as the suction head nears the magazine and to cause a reverse movement of the vacuum-producing means as the suction head moves away from the negative support.

21. In a photographic printing machine, a supporting frame having a vertically disposed magazine at one end, a horizontally disposed printing frame at the other end and an intermediate compartment below the level of the supporting frame for receiving printed negatives, a manually operable conveyor movable into position over the magazine, then automatically acting to pick up a sheet and manually movable into position over the printing frame and during this period holding the sheet and manually movable away from the printing frame and automatically releasing the sheet as the conveyor reaches a position immediately over the compartment for receiving printed negatives, means disposed within the magazine urging the sheets upward through the magazine, and means for separating the top sheet in the magazine from the sheets just before the conveyor reaches the magazine to thereby prevent two sheets from being carried upward by the conveyor.

In testimony whereof I hereunto affix my signature.

ALFRED M. THOMAS.
